UNITED STATES PATENT OFFICE.

FRED MATHEWS, OF CHICAGO, ILLINOIS, ASSIGNOR TO CLINTON C. MURPHY, OF CHICAGO, ILLINOIS.

CAR-ROOF CONSTRUCTION

1,137,347.

Specification of Letters Patent. Patented Apr. 27, 1915.

Application filed July 15, 1912. Serial No. 709,494.

To all whom it may concern:

Be it known that I, FRED MATHEWS, a citizen of the United States, residing at Chicago, in the county of Cook and State of Illinois, have invented certain new and useful Improvements in Car-Roof Constructions, of which the following is a specification.

My invention relates to the construction 10 of railway car roofs, and the invention has for its object to provide a new and improved roof suitable particularly for box cars which may be made entirely of metal.

A further object is to provide a roof in 15 which the roof sheets, and if desired also the purlins, have a loose or floating relation, with the carlines so that they have some capacity for shifting when the car weaves. At the same time the form and construction of 20 the carline is such as to reinforce and rigidify the car so that the tendency to weave is checked so far as it is possible to check it. By giving the roof sheets and purlins a floating or impositive engagement with the 25 rest of the body structure of the car the roof has a certain flexibility which prevents it from being injured or destroyed under the weaving strains which at best can never be entirely prevented.

30 A further object is to provide a metal car roof which will be perfectly water-proof and also impervious to dust, sparks, and the like.

A further object is to provide a roof which will be very strong and durable and at the 35 same time light and comparatively inexpensive to build.

A further object is to provide a car roof construction having the new and improved features and consisting of the novel devices, 40 arrangements and combinations shown in the drawings and which will be hereinafter described and claimed.

The invention is illustrated, in a preferred embodiment, in the accompanying drawings, 45 wherein—

Figure 1 is a fragmentary plan view of the structure, certain parts being broken away for convenience of illustration. Fig. 2 is a sectional view taken on line 2—2 of Fig. 1, looking in the direction of the arrows. Fig. 3 is an enlarged detail section taken on the same line, showing more clearly the constructions and arrangements at one side of the car. Fig. 4 is a side elevation. 50 Fig. 5 is a sectional view taken on line 5—5

of Fig. 1, looking in the direction of the arrows, the view being extended, however, to illustrate one end of the car. Fig. 6, a detail section, on an enlarged scale, taken on the same line but showing only one of the carlines. Fig. 7 is a fragmentary view, in perspective, of one of the roof sheets. Fig. 8 is a fragmentary plan view illustrating the connection between one of the carlines and the side plate. Fig. 9 is a view, in perspective, of one of the carlines. Fig. 10 is a similar view of one of the roof sheet caps. Fig. 11 is a view, in perspective, of a preferred form of bolt for securing the roof sheet cap to the carline, and Figs. 12 and 13 are views, 65 in perspective, of one of the intermediate purlins and one of the end purlins, respectively.

Like characters of reference designate 70 like parts in the several figures of the drawings.

Referring to the drawings which show only as much of the car as is necessary for the understanding of my invention, 75 designates the side plates of the car, 26 the end plates, 27 the ridge pole, 28 the outer side sheathing, 29 the inner side sheathing, 30 the end sheathing and 31 and 32 the side and end fascia plates, respectively. It will be understood that this particular construction of car is used simply for the purpose of illustrating the application of my invention to a car of standard type. The roof structure constituting my invention might be employed, with suitable changes obvious to 80 the mechanic, upon cars of different construction from that shown.

The roof structure of my present invention, in its preferred form, consists of a number of carlines A, purlins B, B', roof sheets C, C' and roof sheet caps D. The carlines consist, in each instances, of an I-beam (Fig. 9) turned sideways with the downwardly projecting webs 33 cut away at each end so that the connecting web 34 lies flat 85 on the side plates 25, 25. The connecting web 34 projects beyond the upstanding webs 35 at each end of the carline and the projecting portions are bent over to form the flanges 36 which overlap the side plate and are secured thereto by the bolts 37. As the downwardly projecting webs 33 of the I-beam carline abut against the inner surfaces 90 of the side plates 25 a very rigid structure is produced which is capable of withstand- 105

110

ing, to a considerable extent, the tendency which railway box cars have to weave. In order to increase the strength and rigidity of the structure gusset plates 38 may be employed which are secured to the vertical webs of the carlines by the rivets 39 and are fastened on the side plates 25 by the bolts 40 (Fig. 8).

The purlins B, B' are formed preferably of T-section bars. The purlins B (Fig. 12) which extend from one carline to the next are provided at each end with a hook 41 formed by cutting off the ends of the upstanding web 42 and bending into substantially U-shape the projecting extremities of the top web 43. The upstanding webs 35 of the carlines are preferably formed with the notches 44 at the places where the purlins hook onto the carlines. The purlins B' (Fig. 13) at the ends of the car are formed, in each case, at one end with a hook 41. At the other end the projecting portion 45 of the top flange is left straight and bears upon the end plate 26 to which it may be secured by, for example, the screw 46 (Fig. 5).

The roof sheets preferably extend from side to side of the car, resting upon the carlines and purlins. The intermediate roof sheets C (Fig. 7) are provided at each transverse margin with a curved portion formed by giving the metal the reversed bends 47, 48. The extreme edges of the sheets are preferably bent to form horizontal flanges 49. The longitudinal edges of the roof sheets (having reference to the length of the car) are formed with depending flanges 50 which overlap the side fascia plates 31. The end roof sheets C' are the same as the structures just described except that their outer edges instead of being formed with the reversed bends are flat and provided with flanges 51 overlapping the end fascia plates of the car.

The roof sheet caps D (Fig. 10) are channel members which, in each instance, extend over a carline and the edges of adjacent roof sheets, the caps bearing upon the horizontal flanges 49 at the edges of the roof sheets. The caps are formed at the ends with flanges 52 secured to the side wall structure of the car by the bolts 53 (Figs. 2 and 4). Preferably the ends of the caps are formed with openings 54 to permit the outflow of any water which may work into the channels formed by the bends 48 in the edges of the roof sheets. The cap pieces D are secured to the carlines A preferably by means of

bolts 55 which extend through the cap pieces and the horizontal webs of the carlines. In order to prevent water from entering the car through the bolt holes the under sides of the heads of the bolts 55 are formed with grooves 56 into which project flanges 57 formed on the cap pieces.

If the car is constructed with a ridge pole 65 the carlines rest upon the latter, designated 27 in the drawings, and may be secured thereto by bolts 58. The running board 59 may be supported on saddles 60 which extend over the roof sheet caps D. 70

It will be understood from the above description that while the carlines are firmly attached to the side walls of the car so as to rigidify the car body, the other elements of the roof, the roof sheets and purlins, are 75 so arranged as to be capable of shifting in case the car body suffers the pulsating, oblique distortions known as weaving. The cap pieces D hold the purlins and roof sheets from displacement. At the same time they 80 do not prevent the latter elements from shifting slightly so as to accommodate themselves to the inevitable weaving of the car. There are no perforations in any of the elements forming the roof except the perforations 85 for the bolts 55. The bosses or flanges 56 prevent any water from working in around the bolts 55. If water works in under the edges of the cap pieces it is intercepted in the U-shaped bends 48 of the roof 90 sheet and is discharged through the openings 54 in the ends of the cap pieces.

While I have described my invention in certain preferred constructions it will be readily understood that some modifications 95 might be made without departure from the invention.

I claim:

In a roof construction for railway cars, the combination of carlines formed to provide channels opening upwardly and roof sheets between said carlines, the margins of which are formed with substantially U-shaped bends terminating in horizontal flanges, the bends lying in the channels of 100 the carlines, caps extending over said carlines and the edges of adjacent roof sheets which bear upon said horizontal flanges, and means for binding the caps against said flanges. 105

FRED MATHEWS.
